ELECTRIC HAND TOOL

Robert Schümann, Dusseldorf, Germany

Application January 24, 1933, Serial No. 653,308
In Germany January 25, 1932

3 Claims. (Cl. 144—32)

This invention relates to an electric hand tool for tightening and loosening screws, in which between the driving element driven by the motor and the tool serving for engaging the screws a friction clutch is fitted, the driving and driven parts of which are pressed together until they mutually contact against the action of a spring by pressing the tool towards the workpiece.

The object of the invention is to produce a tool of the above mentioned kind in which the pressure exerted by the operator for pressing the tool against the workpiece cannot exceed the turning movement necessary for the individual sizes of screws, so that, whilst ensuring against overturning of the screw, there is a control that the screw is sufficiently strongly tightened and it is possible to adjust the turning movement for the individual sizes of screws. In the known tools of the aforementioned type the turning movement exerted on the portion of the tool engaging the workpiece is merely determined by the pressure exerted on the tool which can lead to the overturning of the screw to be tightened or to an insufficiently strong tightening of the screw.

With clutches the parts of which are adapted to be pressed together against adjustable spring pressure for transmitting the power from the drive to the portion of the tool engaging the workpiece the driving moment is certainly adjustable according to the size of the screws actually to be tightened but either the portion of the tool engaging the workpiece must also be continually co-rotated even when the tool is not in engagement with the workpiece, which makes it difficult to bring the tool on to the workpiece, or another clutch or separate device must be fitted which disconnects the portion of the tool engaging the workpiece from the drive when the tool is removed from the workpiece.

An embodiment of the invention is illustrated by way of example in the accompanying drawing in which:—

Fig. 1 shows in longitudinal section the main portion of the tool according to the invention.

Fig. 1a is a top plan view of the gearing of the tool.

Fig. 2 shows in elevation a portion of the tool illustrated in Fig. 1.

Fig. 3 is a part cross section on line III—III of Fig. 1.

Fig. 3a is a part cross-section on line IIIa—IIIa of Fig. 1.

A small high speed electric motor is mounted in the handle sleeve partly shown in the drawing 55 and composed of a tube preferably made of insu-

lating material with a cover 4 of elastic insulating material, such as fluted rubber. The shaft 17 of the motor carries a blade wheel 18. The transmission of movement from the motor shaft to the gearing 34 is effected by a coupling 35. The gearing 34 comprises the pinion 36 coupled with the motor shaft 17 and in which the diametrically opposite toothed wheels 38 engage. Below the toothed wheels 38 two likewise diametrically opposite toothed wheels 39 are arranged which mesh with pinions 40 keyed one on each of the shafts of the toothed wheels 38. Pinions 41 keyed on the shaft of the toothed wheels 39 mesh at diametrically opposite points with a toothed wheel 31. The toothed wheel 37 is keyed on a 10 spindle 42 which in turn is connected with the clutch half 43 of the friction clutch composed of the halves 43 and 33. The clutch half 43 is keyed on the spindle 42 and continually rotates therewith. 42' is a bearing sleeve for the spindle 42 inserted in the head containing the gearing 34. Discs 45 and 46 serve as coupling elements of the clutch halves 43 and 33, the disc 45 having embedded and slightly projecting cork plates 47, whereas the discs 46 are polished. Grooves are 20 provided one in the outer edge of each of the discs 45 and in which grooves a wedge 44 provided in the cylindrical portion of the clutch half 33 surrounding the clutch discs 45 and 46 engages (Fig. 3). Grooves are likewise provided 25 one in the inner edge of each of the discs 46 and a wedge 48 provided in the clutch half 43 engages therein (Fig. 3a). The discs 46 are rotated by the clutch half 43 through the intermediary of the wedge 48, whereas the discs 45, when rotated by the discs 46, rotate the clutch half 33 through the intermediary of the wedge 44.

An adjustable stop is provided between the clutch half 33 and the clutch half 43. This stop consists of a nut 49 screwed by means of a fine 40 screw thread on to the spindle 42. Below the nut 49 a supporting ball bearing 50 is provided against which the clutch half 33 bears when the tool is pressed against the workpiece. A ball bearing 51 serves as supporting bearing for the 45 clutch half 43. The clutch is held together by a cap nut 52. A centering sleeve 55 is provided on the clutch half 33 for receiving the tool. An aperture is provided in the clutch element 33, which is hollow and surrounds the nut 49, to give 50 access to the nut (Fig. 2). The bores 53 in the nut 49 serve for inserting a pin for adjusting the nut. As the spindle 42 must be held during the adjusting of the nut, a bore 54 is provided in the spindle 42 and extended through the clutch 55

halves 43 and 33 for the insertion of a pin for holding the spindle. It is evident that, when adjusting the nut, the clutch half 33 must be turned into a position in which the portion of the bore 54 therein registers with the portion of the same bore 54 in the spindle 42 and in the clutch half 43 keyed thereon. For controlling the position of the nut 49 the nut is equipped with a scale and a mark 56 is provided on the clutch half 33. As for adjusting the nut 49 the clutch half 33 must always be first turned into the position which allows the insertion of the holding pin into the bore 54, scale of the nut is brought in its zero position relative to the mark 56 so that, when adjusting the nut, the mark allows the degree of adjustment to be read on the scale.

The spring 82 bears against the upper edge of the clutch half 33 and presses the clutch halves apart so that the clutch half 43 does not drive the clutch half 33. When the tool is pressed against the workpiece, the clutch half 33 shifts upwards, compressing the spring 82, so that the clutch elements 45 and 46 or the cork plates 47 on the discs 48 and the discs 46 come into contact. The movement of the clutch half 33 is limited by the nut 49 against which the clutch half 33 bears through the intermediary of the supporting ball bearing 50. If the nut is screwed upwards the clutch half 33 can shift further in upward direction so that the clutch elements 45 and 46 are pressed more strongly together. When the nut is screwed downwards, the clutch half 33 cannot shift so far in upward direction so that the clutch elements are pressed together less strongly. Therefore by shifting the nut, the intensity of the contact between the clutch halves

and consequently the turning moment to be transmitted can be regulated as desired so that the tool can be adjusted for different sizes of screws.

The motor employed for the tool is reversible so that the tool can be employed for screws with left and right hand screw threads and for tightening and loosening screws.

I claim:

1. An electric hand tool for tightening and loosening screws, comprising in combination a driving spindle, a stationary clutch half on said spindle, a movable clutch half surrounding said stationary clutch half and axially shiftable relative to said stationary half, a tool carrying sleeve on the lower end of said movable clutch half, said movable clutch half adapted to bear against said stationary clutch half to transmit the movement of said driving spindle to said tool carrying sleeve when the tool is pressed against the workpiece, and an adjustable stop in the path of movement of said movable clutch half adapted to limit the displacement of said movable clutch half and determine the intensity of contact between said two clutch halves.

2. An electric hand tool as specified in claim 1, in which the adjustable stop consists of a screw nut on the driving spindle, said nut forming an abutment for the movable clutch half when the tool is pressed against the workpiece.

3. An electric hand tool as specified in claim 1, in which the adjustable stop consists of a screw nut on the driving spindle and the movable clutch half is constructed as a hollow body surrounding said nut and having an aperture giving access to said nut to allow of its adjustment.

ROBERT SCHÜMANN.
